UNITED STATES PATENT OFFICE.

TIMOTHY J. COLLINS, OF TOLEDO, OHIO, ASSIGNOR TO JOHN R. B. RANSOM AND THADDEUS F. RANDOLPH, BOTH OF SAME PLACE.

DESIGN FOR A DENTAL CABINET.

SPECIFICATION forming part of **Design No. 20,582**, dated **March 17, 1891**.

Application filed February 2, 1891. Serial No. 379,935. Term of patent 14 years.

To all whom it may concern:

Be it known that I, TIMOTHY J. COLLINS, of Toledo, county of Lucas, and State of Ohio, have invented and produced a new and original Design for Dental Cabinets; and I do hereby declare that the following is a full, clear, and exact description of the invention, which will enable others skilled in the art to which it appertains to make and use the same, reference being had to the accompanying drawing, and to the letters of reference marked thereon, which forms part of this specification.

The drawing represents a perspective view of my newly-designed dental cabinet.

15 The leading features consist of a base 1, in which are a series of drawers 2 upon one side and a door 3 upon the opposite side ornamented with panels 4 of an area to alternate with the area of the drawers 2, there being a 20 series of drawers 5 surmounting and extending across the door and panels, with a cabinet 6 resting upon the base and above the drawers 5. Said cabinet is embellished with panel-doors 7, which open into an inner receptacle 25 8, divided into compartments 9, supplied with drawers 10 of a width to harmonize with the

base portion. The cabinet is surmounted with an ornamental top 11, having a central elevation 12, in which is a panel-mirror 13 centrally of the panels of doors 7, the top portion extending from the elevation in a graceful scroll to a base 14 upon each side and embellished with a scroll-work 15 in flat relief to harmonize with a like portion 16 at the foot of the base. The entire cabinet as thus embellished presents a highly ornamental and symmetrical appearance.

30 35 What I claim is—

The design for a dental cabinet herein described, consisting of a base divided by drawers and a panel-door and a cabinet centrally divided by panel-doors opening into a compartment-recess, with a top surmounting the same having a central panel-mirror and a scroll top having the ornamentation shown.

40 45 In testimony that I claim the foregoing as my own I hereby affix my signature in presence of two witnesses.

TIMOTHY J. COLLINS.
